UNITED STATES PATENT OFFICE

146,858

DESIGN FOR AN ELECTRIC IRON

Clarence Karstadt, Glen Ellyn, Ill., assignor to
Noblitt-Sparks Industries, Incorporated, Co-
lumbus, Ind., a corporation of Indiana

Application October 29, 1945, Serial No. 123,266

Term of patent 7 years

(Cl. D49—6)

To all whom it may concern:

Be it known, that I, Clarence Karstadt, a citizen of the United States, residing at Glen Ellyn, DuPage County, Illinois, have invented a new, original, and ornamental Design for an Electric Iron, of which the following is a specification, reference being had to the accompanying drawing, forming part thereof.

Fig. 1 is a perspective view of an electric iron embodying my new design; Fig. 2 is a plan view; and Fig. 3 is a side elevation thereof.

I claim:

The ornamental design for an electric iron, as shown.

CLARENCE KARSTADT.
